UNITED STATES PATENT OFFICE.

ARCHIE P. McLARTY, OF DENVER, COLORADO.

HYDRAULIC CLAMP.

No. 856,416.

Specification of Letters Patent.

Patented June 11, 1907.

Application filed December 11, 1905. Serial No. 291,367.

To all whom it may concern:

Be it known that I, ARCHIE P. McLARTY, a citizen of the United States of America, residing at the city and county of Denver and State 5 of Colorado, have invented a new and useful Hydraulic Clamp, of which the following is a specification:

My invention relates to improvements in hydraulic clamps; and the objects of my invention are: First, to provide a hydraulic wood gluing clamp. Second, to provide a hydraulic clamp especially adapted to clamp together the several members of doors, window frames, and built-up veneered wood- 15 work, at the time they are coated with glue and are assembled together ready to be clamped together until the glue dries. Third, to provide a hydraulic clamp that can be used for clamping together or compressing 20 any material that requires a steady, constant, pressure, in the course of its manufacture. I attain these objects by the mechanism illustrated in the accompanying drawings, in which:

Figure 1, is a plan view of the form of hydraulic clamp, which is especially adapted for clamping doors, window sashes, blinds, shutters, and the like, a door being shown in the act of being clamped. Fig. 2, is an end 25 elevation of the same. Fig. 3, is a longitudinal sectional view through one of the water cylinders, showing the inlet and outlet pipes, the supporting beam, a portion of one of the stringers, and the push bar, which rests upon the stringers, and is operated by the piston rods of the cylinders. Fig. 4, is a perspective view of one of the abutment blocks, and the rod to which it is rigidly secured, together 30 with the yoke which engages the notched 35 stringers, and the lever, for moving said yoke out of engagement with the notches. Fig. 5, is an elevation of a vertical clamp embodying my improvements, which is especially adapted for small work, such as clamping short 40 lengths of board or strips of wood together. Fig. 6, is a horizontal, sectional view thereof, on the line 6—6 of Fig. 5. Fig. 7, is a horizontal, sectional view on the line 7—7 of Fig. 5. Fig. 8, is an elevation of a vertical type of 45 clamp, in which a pair of clamps are adapted to work independently or together, enabling the machine to be used either for long or short work. Fig. 9, is a horizontal, sectional view thereof, on the line 9—9 of Fig. 8. Fig. 10, 50 is a transverse, sectional view through the

abutment plate and upper framework of this type of clamp, showing the manner of throwing the yokes out of engagement with the notched standards, and for raising and lowering the plate, and holding it at the desired 60 point when pressure from beneath is removed. Fig. 11, is an elevation of a form of clamp adapted for long strips. And Fig. 12, is an end elevation thereof.

Similar letters of reference refer to similar 65 parts throughout the several views.

Referring to the drawings: The numeral 1, designates the frame work of a hydraulic clamp, embodying my inventions. This frame work may be made of either wood or 70 iron or partially of both.

In the drawings, I have illustrated several different types of my invention. They are all alike, however, in their principal features, but have been arranged for different characters of wood gluing work.

At one side of the frame work of the type of machine illustrated in Fig. 1, which I term the horizontal type, the frame consists of a beam 1A, which I term the head end beam, 80 and which forms one end of the horizontal machine. This beam is supported at a short distance above the floor on legs 2 and 3, which are secured at one of their ends to the beam, and the legs are secured at their opposite ends to the floor. To the head end beam, I secure one of the ends of a plurality of flat iron bars, 4, which I call frame stringers. These stringers extend from the head end beam at right angles to it, and are spaced at 85 a short distance apart, or at about such a distance apart that it will require four or five or six of them to form a hydraulic clamp long enough to receive and glue up the largest and longest sizes of doors. I preferably use five 90 of these bed stringers in a machine especially adapted for gluing up doors. The opposite ends of these stringers are free and open, and each stringer is supported by a leg 5, which extends to the floor and is of a length to make 95 all of the stringers of the same even horizontal height, so that top edges will form collectively a bed frame upon which different sized doors, window frames, and all characters of wood-work that are to be glued together, are placed. The lower edges of these stringers are provided with a plurality of notches 6, which are preferably inclined from the edge rearward toward the free ends of 100 the stringers, and across the top of the bed 105

stringers I lay loosely a beam 7, which I call an abutment beam, and on the farther side of this abutment beam from the head end beam I place on top of each stringer an abutment block 8, and loosely through these blocks I extend a rod 9, which extends through the blocks transversely to the length of the stringers, and parallel with the head end beam. To this rod 9, I secure a yoke shaped staple 10, at each abutment block 8, arranging the ends of the staples to surround the lower edge of each abutment block, and to be securely keyed to the rod while the yoke or loop of each staple hangs down and surrounds and slides loosely along the bed stringers. The end of the loop or yoke is made to fit freely into the notches along the lower edges of the stringers, and when the staples are tilted forward toward the head end beam, and the abutment blocks are drawn backward toward the free ends of the stringers, the loop ends of the staples catch in the notches and lock the abutment blocks rigidly to the stringers. It is necessary, however, in operating the machine that all of these abutment blocks be locked across the stringers exactly at right angles to them, and parallel to the head end block, and also that they be all moved or shifted together along the stringers. I accomplish this by securing to the rod 9, a lever 11, which I also either provide with a weight or make heavy enough to act as a weight and secure it to extend rearwardly of the rod, so that its weight will normally hold the staples inclined at a forward downward angle in a position to enable its loop end to readily engage the notches of the stringers. I preferably secure this lever centrally between the first two stringers from the end of the clamp, at which the water controlling valve and lever are placed, in order to be handy for the operator. The lever is pivotally secured to a hub 12, which is rigidly attached to the rod centrally between the stringers, the inner end of the lever being formed with a yoke 13, which is pivotally secured to the hub by screws or pins 14, which form trunnions for the ends of the yoke and thus permit the lever to be swung laterally between the two stringers. An arm 7A, is secured to the under side of the abutment beam 7, and extends rearwardly adjacent to the lever 11, its outer end being formed with a right angled member, which extends toward the lever. Now when the lever is raised to throw the yokes 10, out of engagement with the notches in the under edges of the stringers, the yokes may be held in this position by moving the lever to one side so that it may rest upon the arm 7A. To the head end beam, I secure a plurality of hydraulic cylinders 15, preferably employing as many cylinders as there are bed stringers in a machine, placing each cylinder in direct longitudinal alinement with each

stringer, so that the pressure of each cylinder will be in direct longitudinal alinement with its respective stringer and against its abutment block.

In each cylinder, I mount a suitable hydraulic piston head 17, which is provided with a cupped washer 18, of leather or rubber or any other suitable material, and a follower 19, which is secured to the head by a bolt 20, and is arranged in such a manner as to clamp the cupped washer to the head. The cupped washer forms a packing ring around the piston head that is arranged to fit tightly but slidably in the cylinder. A piston rod 21, is secured to the piston head, and extends through the front cylinder head 22. A rear cylinder head 23, is also secured to the cylinder in any suitable manner. The piston rod of each cylinder projects slidably through the front cylinder head of its respective cylinder, and extends to a cross bar 24, that I call the push bar. This lies slidably on top of the stringers, and the two piston rods at the opposite ends of the frame are secured to the push bar, preferably by a cap screw bolt 25, which is screwed into the end of the piston from the opposite side of the bar, the head of which is countersunk into the push bar. The intermedial piston rods have square ends, and they bear against the side of the bar. This arrangement prevents any twisting or torsional strains on the push bar, which is carried by the two end cylinders to and from the glued work, and permits the intermediate pistons to have independent freedom of reciprocative action in exerting pressure against the push bar, and glued work and in retreating from them.

To the front cylinder head of each cylinder, I connect a drip pipe 26, each pipe connecting with a general waste pipe 27. These drip pipes and the waste pipe are arranged and adapted to convey the water that leaks past the cupped packing ring into the front end of the cylinder to waste, or to a reservoir or tank for re-use.

To the front end of each of the front cylinder heads, I connect a water inlet nipple 28, and to the nipple of each cylinder head, I connect a quick-closing valve 29, which is operated by a lever 29A, and to each valve a short depending pipe 30, which pipes connect to a common water supply pipe 31, that extends along all the cylinders, and at one end connects to a source of water under pressure, such as a city water pressure, or to a pump and storage tank, the pump being arranged to draw water from the storage tank and provide the water pressure, which may be accomplished by pumping directly into the pipes or into a storage receiver, where the water is kept under pressure, the water supply pipe being connected directly to the water receiver. I preferably use a pump, and connect it to a supply of water in

a well or tank, and pump into a storage receiver, where the water is kept under pressure, connecting the end of the supply pipe to the storage receiver. A general water supply pipe 32, is connected to the pipe 31, by a three-way valve 33, which is operated by a lever 34, and between the three-way valve and the first water cylinder the pipe 31 is provided with a pressure-regulating valve 35. The remaining side of the three-way valve connects with a return pipe 35A, and the general supply pipe has a valve 35B, by which the supply of water may be cut off when desired. In Fig. 1, the three-way valve is turned to allow the water from the general supply to enter the cylinders, through the common supply pipe 31, and vertical pipes 30, the return pipe being cut out, but when the operating lever 34, is turned in the direction of the arrow, and at right angles to its present position, the supply is cut off, and the water from the cylinders passes back through pipe 31, through the three-way valve, and out through the return pipe. One or more of the levers 29A, of the cylinder valves, may be pivotally attached to a horizontal connecting rod 35C, one end of which is pivotally attached to a hand lever 35D, which is pivoted at its lower end to a bracket secured to the floor, the lever being within convenient reach of the attendant, and by moving this lever in the proper direction the water supply is cut off from the cylinders which are connected with it, for a purpose to be hereinafter described. The opposite terminal end of the water supply pipe 31, extends to the last cylinder, and a reducer is connected to it, from which a small pipe extends to a pressure gage 36, which is placed in sight of the operator of the hydraulic clamp. The various valves and levers are located at the end of the machine at which the operator works when inserting and withdrawing the glued work, the end selected depending on the position and surroundings of the machine in the planing mill in which it is placed; consequently, these valves are within easy reach of the operator when standing at this end of the machine. The opposite site end of the water return pipe leads to the well or supply tank, from which the pump takes its supply. The water return pipe conveys the waste water from all of the cylinders back to its source of supply, when the water pressure is cut off, after work has been subjected to pressure, and the glue is dry, as will be explained fully hereinafter.

The water pressure moves the pistons on their forward strokes only, in their respective cylinders, and while I could arrange the water pressure to move the pistons on their backward stroke, I preferably use a counter-weight, which I arrange in the following manner: To the push bar 24, between each pair of stringers, I secure one of the ends of a

wire cord or chain 37, which extend back over pulleys 38, that are pivotally mounted on the head end beam, and down through holes in the beam, and to their opposite ends I secure a heavy bar or beam 39, which is 7c long enough to extend across from the first to the last cord. Thus when the water pressure is shut off from the cylinders, the weight of this bar pulls the push bar back, and it pushes the piston rods and pistons back into 75 the cylinders, and forces the water out of the cylinders through the same pipes and valves by which it entered, as has been previously described.

The cylinders are all arranged so any one 80 or two or three of them, may be cut off from the water pressure when it is desired to use it on the balance, which is desirable when doors or wooden pieces are to be glued together that are shorter than the length of the machine, in which case only enough cylinders are used to extend the pressure throughout the length of the work to be glued. Consequently, all the cylinders may be cut off by closing their valves, except one or two or 90 more, as the work requires, while the water pressure would flow to and operate the other.

In Figs. 5, 6, and 7, I illustrate a different style of my improved hydraulic clamp than that shown in Figs. 1, 2, 3, and 4. This style 95 of machine embodies all of the essential features of the horizontal style, which are a hydraulic cylinder with suitable water controlling inlet and discharge pipes and valve, a bed plate upon which the work to be glued is 100 laid, an adjustable abutment member, and a suitable frame adapted to support these members in a vertical position. This frame consists of the two opposite standards 41 and 42, which are secured at their floor ends to a 105 cross piece 43, that is wide enough to form a bed plate, and which is secured to the floor, and at their upper ends the standards are connected together by a cross brace 44. The cylinder 45, is mounted on the bed plate, and 110 is provided with a flanged cylinder head 46, that is bolted to the bed plate. This cylinder is provided with a water inlet pipe 47, and water discharge pipe 48, which connect together close to the cylinder, a three-way 115 valve 49, being inserted in them at their junction. The cylinder is also provided with a piston rod and head, the same as the cylinder in the horizontal style, and to the end of the piston a flat square shaped table 48A, is 120 secured, the opposite sides of which are provided with recesses that fit loosely over the adjacent edges of the vertical standards, which act as slideways for the table as it is moved up and down by the reciprocal movements of the piston. This table, while it is 125 of different shape from the push bar of the horizontal clamp, performs the same function, as it applies the pressure of the piston to the work, and at the same time acts as the 130

supporting table of the machine. Above this table I place an abutment plate 48B, which is of the same size as the table, and is slidably positioned between the standards, 5 the edges of which extend into recesses in two of its opposite sides. The center of this abutment plate is provided with a hub 49A, which is secured to a cross head 50, which consists of two parallel bars that are secured 10 to the hub of the plate, the opposite ends of which extend over and slide on the adjacent sides of the standards. Both standards are provided with a vertical row of pin holes 51, in which pins 52, are inserted above the cross 15 head to hold the abutment plate in adjusted positions. Adjacent to the opposite ends of the cross bars of the cross head, I place two pins 53, to which I secure the opposite ends of a bail 54, the center of which is connected 20 to a hook or loop that forms one end of a rope 55, the opposite end of which extends over a pulley 56, that is pivotally attached to the ceiling, and is attached to a weight 57. While this weight and the ropes and abutment 25 plate are of different construction from the abutment bar and ratchet and loops and locking lever of the horizontal machine, they nevertheless perform the same functions and are consequently equivalent to that mechanism.

In Figs. 8, 9, and 10, I have applied my invention to another form of clamp, comprising two independent clamps, which are arranged to be used in unison, when very long 35 boards are to be glued, or independently, when shorter boards are to be glued. Upon a suitable foundation is secured a plurality of the water cylinders, preferably four, and these cylinders are all connected at their 40 lower ends by supply pipes 58, 58A and 58B, and at their upper ends by a return pipe 59. These cylinders are similar to those illustrated in the other forms of this invention, and to the upper ends of the pistons of each 45 pair of cylinders is secured a bed plate 60. Standards 61, of any desired height, are secured to the floor, and extend upward on each side of the two bed plates. These standards are located at points on a line with 50 the axial centers of the cylinders, so that there are a pair of oppositely positioned standards for each cylinder. The standards on one side are connected at their upper ends by side strips 62, and each oppositely arranged pair are connected by cross braces 63. 55 Abutment plates 64, of the same size and shape as the bed plates, are supported above the bed plates and between the standards, by bails, to which cables are secured that pass 60 over pulley wheels, and are provided at their free ends with counter-balancing weights the same as is shown in Fig. 5. The standards are notched on their outer edges as shown at 65, Fig. 10, and the abutment plates are held 65 at a given point against upward movement in

the following manner: A pair of metal bars or strips 66, are suitably secured edgewise upon the top of each abutment plate, one between each pair of standards, and at each end of each of these strips, is pivoted a yoke 70 67, similar to that shown in Figs. 2 and 4, the lower ends of which engage the notches 65 of the standards. Each pair of yokes are thrown out of engagement with the notches 75 by rods 68, attached at one end near the lower ends of the yokes, and at their opposite ends to the opposite ends of a rock arm 69, secured to a rock shaft 70, which is supported by the bars 66. The rock shaft is provided with lever 71, by which it is rocked 80 to throw the yokes out of engagement with the notches of the standards. The abutment plates are raised or lowered to the desired position, by cords or cables 72, which are suitably attached to the plates, and to 85 spools 73, on the ends of a rod 74, which is supported in bearings or brackets 75, attached to the cross bars or braces of the standard frame. One end of the rod is provided with a crank handle 76, and the rod is 90 further provided with a ratchet wheel 77, which is engaged by a pawl 78, so that the abutment plate will be prevented from slipping down, when the upward pressure, excited by the bed plate, is removed, as when 95 glued material is being removed from between the plates. The water cylinders or jacks may all be operated at once, or each pair, which operate the separate bed plates, may be operated separately, and to accomplish this the following arrangement of pipes and valves is employed: The pipe 58A, connecting the two inner cylinders, is provided with a cut-off valve 79, and the pipes 58 and 58B, connecting the outer cylinders with the 100 adjacent inner cylinder, are provided with tees 80, to which are connected short pipes 81 and 82 respectively, provided with three-way quick closing valves 83 and 84, which connect with a water inlet pipe 85, and with 105 a return pipe, 86, the latter having a cut-off valve 87. Now, when it is desired to operate all of the cylinders at once, the valve 87 in the return pipe is closed, valve 79 opened, and valve 84, turned to connect the inlet 110 pipe with the cylinder pipes 58B, the valve 83, being closed to the inlet pipe. The water will then enter through the valve 84, and pass in to all the cylinders, through pipes 58B, 58A, and 58, and when the valve 84 is 115 reversed, the water will pass from the cylinders back through these pipes and the valve 84, to the return pipe 86. When it is desired to use either pair of cylinders independently of the other pair, the valve 87, in 120 the return pipe is opened, and the valve 79, between the two inner cylinders closed; then either the valve 83 or 84, as may be desired, may be turned to connect the water supply 125 with the adjacent pair of cylinders, the valve 130

of the cut-off cylinders being closed against the supply, and when the valve of the operating cylinders is reversed, the water will flow out through the return pipe, as when all the cylinders are employed. The air in the upper end of the cylinders, and any water that may have worked past the piston heads, will escape through the pipe 59.

In Figs. 11 and 12, I illustrate a form of clamp which is especially adapted for long strips or narrow boards, and to this end I employ a plurality of uprights or standards 88, five being shown, to the lower end of each of which is suitably secured a water cylinder 89, similar to those illustrated in other of the figures, with the exception that the water enters centrally through the lower cylinder head. These cylinders are adapted to work in unison and operate a single bed plate 89A. The abutment plate 90, is braced at intervals, corresponding to number and position of the uprights, by blocks 91, which are braced by a strip 92. The rear sides of the uprights are formed with notches 93, and to each block is pivoted a bail or yoke 94, which is adapted to engage these notches, when pressure is applied to the under side of the abutment plate, and the plate is raised and lowered, as in the forms illustrated in Figs. 5 and 8. The cylinders are connected by valves 95, with a supply pipe 96, which at one end is provided with a valve that is closed, when the pressure is on, but is opened when the supply is cut off, and the cylinder valves are turned, to permit the water to escape from the cylinders. Each cylinder may have an independent valve, or the three inner cylinders may be connected by one pipe and operated by a single valve, while the end cylinders have independent valves, or all the cylinder valves may be connected, as illustrated in Figs. 1 and 2, and operated simultaneously by a hand lever.

In operation, the abutment plate, or beam, as the case may be, is moved to the desired point, and held against further movement by the notch-engaging yokes; the article or articles to be clamped are placed upon the bed plate, or against the abutment beam, according as the clamp is of the vertical or horizontal type, and the valve is turned to admit water to the cylinders, the pressure being regulated by the pressure valve. The glued work will then be clamped between the follower and abutment, and held in a clamped position until the glue is dry, when the water under pressure is cut off, and the water in the cylinder passes off through the return pipe, and the follower or push beam returns to its normal position.

My invention, as embodied in the various forms herein illustrated, is adapted for use in all characters of mill work, which are required to be clamped after being glued.

65 The device in its various styles is adapted

for the lightest as well as the heaviest work, and can be operated under any desired pressure, which pressure is equal at all points. The device, moreover, is simple, practical, and easily and quickly operated, and greatly reduces the time and labor required in operating the hand clamps in general use.

Having described the invention, what I claim as new and desire to secure by Letters Patent, is:

75

1. In a clamp of the character described, a frame having notched members; an adjustable abutment on the frame; stops which limit the movement of the abutment in one direction, and means which connect the stops with the notched members; a support at one end of the frame, and a plurality of hydraulic cylinders secured to said support; a follower operated in one direction by the cylinders, and in the opposite direction by a counter-balancing weight, and means for admitting water to all of the cylinders or to any one or more of the cylinders independently of the others.

2. In a clamp of the character described, a supporting frame consisting of notched bars; a follower at one end of the frame; an adjustable abutment beyond the follower; yokes which engage the notched bars to hold the abutment at a desired point, and a lever for disengaging the yokes from the notches; a series of hydraulic cylinders for operating the follower; a valve for controlling the supply of water for the cylinders; independent valves for cutting out any one of the cylinders, and pipes for permitting the escape of air and of any water at the rear end of the cylinder.

3. In a clamp of the character described, a frame composed of horizontal strips having notches upon their edges; stops having pivoted yokes adapted to engage the notches, a lever for disengaging the yokes from the notches, and an abutment which is held at a desired point by the stops; a follower; a plurality of hydraulic cylinders, having plungers which operate the follower in one direction, and a counter-balancing weight for returning the follower to its normal position; inlet pipes for the cylinders which connect with a common supply pipe; a three-way valve connected with the common supply pipe, and with a general supply pipe, and a return pipe; and an independent cut-off valve for each cylinder inlet pipe, whereby one or more cylinders may be rendered inoperative.

4. In a clamp of the character described, a frame made up of horizontal bars which are notched upon their under sides and supported above the floor at each end; a movable stop upon each bar and a rod connecting the stops; yokes which straddle the stops and are rigidly secured to the rod at their upper ends, their lower ends being joined by pins which engage the notches of the bars; a lever

100

105

110

115

120

125

130

for turning the rod to disengage the yokes from the notches, and an abutment which rests against the stops; a follower at the opposite end of the frame; a series of hydraulic cylinders having plungers which operate said follower in one direction, and a weight for returning it to its normal position, and means for delivering water under pressure to each cylinder independently of the others or to all 10 the cylinders in unison.

5. In a clamp for the purpose specified, a series of horizontal bars supported at each end, and provided with notches upon their under edges; movable stops upon the bars, 15 yokes which straddle the stops and bars and engage the notches; a rod which passes through the several stops and yokes and is rigidly secured to the yokes; a lever secured to the rod by which the rod may be turned to 20 disengage the yokes from the notches, and an abutment which rests against the stops; a follower; a series of hydraulic cylinders having plungers for operating the follower, two or more of which are secured to the follower 25 while the remaining plungers are not secured thereto; valved inlet pipes for the cylinders, which are connected with a valved supply pipe, and means whereby the water may be admitted to all the cylinders at once, or to 30 one or more cylinders independently of the others.

6. In a clamp for the purpose specified, the combination with a frame; an adjustable abutment on the frame; a follower; a series 35 of hydraulic cylinders having plungers which move the follower in one direction, and valved inlet pipes which are connected with a common supply pipe, of means for supplying the cylinders independently or in unison, 40 comprising a general supply pipe, a return

pipe, and a three-way valve, which is connected with the cylinder supply pipe, the general supply pipe, and the return pipe; independent levers connected to one or more of the cylinder inlet pipe valves, a rod connecting the said levers, and a hand lever for operating the said rod, whereby one or more of the cylinders may be cut out, and cords attached at one end to the follower, and which extend back over pulleys and connect to a 50 counter-balancing weight. 45

7. In a clamp for the purpose specified, the combination of a frame, having notched bars; a follower; a series of hydraulic cylinders having plungers which operate the follower 55 in one direction, and a weight for returning it to its normal position; means for operating the cylinders independently or in unison; an adjustable abutment; stops which limit the movement of the abutment; yokes which 60 straddle the notched bars and normally engage the notches thereof; a rod which passes through the stops and yokes and is rigidly secured to the yokes; a weighted lever, rigid upon the rod axially, but adapted to have a 65 lateral swinging movement thereon, and an arm secured to the abutment adjacent to the weighted lever, the said lever being adapted to be lifted to turn the rod to free the yokes from the notches, and to be swung to one side 70 so as to rest upon the said arm when it is desired to hold the yokes in an inoperative position. 70

In testimony whereof I affix my signature in presence of two witnesses.

ARCHIE P. McLARTY.
